UNITED STATES PATENT OFFICE.

NATHAN E. CHAPMAN, OF CHICAGO, ILLINOIS, ASSIGNOR TO ILLUMINATING PRODUCTS CO., OF CHICAGO, ILLINOIS, A CORPORATION OF ILLINOIS.

DESIGN FOR AN ELECTRIC-LIGHT FIXTURE.

Application filed October 18, 1926. Serial No. 19,402. Term of patent 3½ years.

To all whom it may concern:

Be it known that I, NATHAN E. CHAPMAN, a citizen of the United States, residing at Chicago, in the county of Cook and State of Illinois, have invented a new, original, and ornamental Design for an Electric-Light Fixture, of which the following is a specification, reference being had to the accompanying drawing, forming part thereof.

In said drawing Figure I is a side elevation of an electric light fixture showing my new design; Figure II is a detail view look-

ing from below of one of the candle plates which forms part of the design, Figure III is a detail side elevation of one of the arm husks which forms part of the design, and Figure IV is a perspective view of the lower portion of the fixture, the view being upon an enlarged scale.

I claim:

The ornamental design for an electric light fixture as shown.

NATHAN E. CHAPMAN.
